UNITED STATES PATENT OFFICE.

STANLEY PASTERNAK, OF CHICAGO, AND JOSEPH PASTERNAK, OF WEST HARVEY,
ILLINOIS.

CURTAIN-STRETCHER.

1,353,067.

Specification of Letters Patent. Patented Sept. 14, 1920.

Application filed December 8, 1919. Serial No. 343,279.

To all whom it may concern:

Be it known that we, STANLEY PASTERNAK and JOSEPH PASTERNAK, respectively, a citizen of the United States of America and a subject of Austria (first U. S. papers), and, respectively, a resident of Chicago, county of Cook, and State of Illinois, and West Harvey, county of Cook, and State of Illinois, have invented certain new and useful Improvements in Curtain-Stretchers, of which the following is a specification.

The main objects of this invention are to provide an improved form of rack or frame for stretching and drying lace curtains and similar pieces of fabric; to provide an improved rack which is assembled in the form of a cylinder and is adapted to stand on end in a vertically disposed position and thereby occupy a minimum amount 20 of space and yet be capable of stretching all regular-sized curtains; to provide an improved form and arrangement of the parts of said rack whereby it is adjustable in order to accommodate curtains of different widths; 25 and to provide a rack of this character which is collapsible so as to occupy a minimum amount of space when not in use.

An illustrative embodiment of this invention is shown in the accompanying drawings, in which—

Figure 1 is a side elevation of an improved form of rack or frame constructed in accordance with this invention.

Fig. 2 is a top plan of the device.

Fig. 3 is a section taken on the line 3—3 of Fig. 1.

Fig. 4 is an enlarged fragmentary sectional view of one of the annular members showing the fastening means for securing 40 the curtain thereto.

Fig. 5 is a fragmentary view of one of the supporting elements.

Figs. 6 and 7 are fragmentary views showing the clamping means for adjustably 45 securing one of the supporting elements to the annular members.

The improved form of device herein shown comprising a plurality of supporting elements or standards 1, an auxiliary supporting element 1.1 and a pair of annular members 2 and 3 which are adapted to be assembled so as to form a cylindrical-shaped frame or rack which is intended to be used by standing it on the ends of the support-

ing elements so that said frame occupies a 55 vertically disposed position as indicated in Fig. 1.

The supporting elements or standards 1 and the standard 1.1 each comprise a pair of parts 4 and 5 connected together by hinges 6 so that said parts may be folded one upon the other when the frame or rack is dismantled for storage or shipping, and which may be extended into longitudinal alignment when said frame is to be set up for 65 use. The part 5 of each standard is provided with a slot 11 extending lengthwise thereof throughout the greater portion of the length and constituting a guideway for clamping members carried on the annular 70 member 3 by means of which said annular member is secured in place, as will more fully hereinafter appear.

Brace plates 7 are arranged on the supporting elements 1 and 1.1 at the hinged 75 connections of the parts 4 and 5 so as to secure said parts in their longitudinally extended relation when the frame is assembled. These plates are rigidly secured to one face of the respective parts 5 by means 80 of bolts 8. The other end of each of the plates 7 is provided with an aperture through which a bolt 9 carried by the part 4 is adapted to extend and have a winged nut 10 screwed home against said plate for 85 firmly holding the parts 4 and 5 thereto.

The annular members 2 and 3 each comprise a pair of arcuate or curved parts or sections 12, the ends of which are connected by braces 13, which strengthen the parts and 90 retain their arcuate form. The sections 12 are connected together by hinges 14 so as to be foldable one upon the other when the rack is dismantled, so that for the purpose of shipping or storage the annular members 95 occupy just one-half the space that would otherwise be required.

When the frame is assembled, the annular member 2 is rigidly secured to the outer or upper ends of the parts 4 of the supporting 100 elements 1 by means of suitable bolts and winged nuts such as constitute the clamping means for the annular member 3, as will more fully hereinafter be described. The other annular member 3 is adjustably supported on the parts 5 of the supporting elements 1 and 1.1 above the lower ends thereof.

The clamping means by which the annular member 3 is adjustably secured in position on the supporting elements 1 comprise bolts 15 secured at certain angular points 5 on the member 3 and extending through the slots 11 and having upon their inner ends winged nuts 16 which are adapted to be screwed up against the corresponding supporting elements 1 so as to clamp said supporting elements and annular member together in fixed relation.

The auxiliary supporting element 1.1 is slidably secured to the annular members so as to be laterally shiftable with respect to 15 the adjacent standards 1.

The clamping means for adjustably securing the standard 1.1 to the annular members each comprise a channel piece 18 which is adapted to embrace and slidably engage the 20 top and side edges of the annular members. The channel piece carries a bolt 19 having a wing nut 20 for attachment to the standard 1.1. The bolt 19 of one of the clamping means is seated in an aperture formed at the 25 upper end of the standard 1.1 and the bolt of the other clamping means slidably engages the slot 11 of the standard 1.1 whereby the annular member 3 may be vertically shifted with respect to the auxiliary stand- 30 ard.

The slot 11 of the auxiliary standard is wider at its outer edge so as to provide a seat for an extension 21 formed on the inner face of the channel piece 18. The extension 35 21 forms a seat for the head of the bolt 19.

The fastening means by which the curtain or similar fabric is secured upon the frame comprise a plurality of pins 17 similar to those generally used in fabric stretching devices of this kind, which pins in this case are secured upon the outer periphery of the annular members 2 and 3. The members 2 and 3 are cut away as indicated in Fig. 4 and the pins 17 secured in place so 40 that the outer ends thereof are substantially in the plane of the outer face of said annular members. Similar fastening means are secured to the auxiliary standard 1.1 and to one of the adjacent supporting elements 45 1 for securing the ends of the curtain.

A device of this kind, constructed as herein set forth so that it may be stood on end in a vertical position, occupies such a small amount of space that it may conveniently be used in small rooms with the same facility as and in many instances greater facility than is obtained with the rectangular-shaped frames. By constructing the supporting elements and the annular members in two parts, hingedly connected together so as to be folded one upon the other, it is possible to store the device in compact form when it is not in use.

The manner of assembling the device and 65 dismantling it is thought to be so obvious,

and the use of devices of this character so well-known, that further description as to these points is deemed unnecessary.

Although but one specific embodiment of this invention has been herein shown and described, it will be understood that some details of the construction shown may be altered or omitted without departing from the spirit of this invention as defined by the following claims.

We claim:

1. In a device of the class described, the combination of a plurality of supporting elements, a pair of annular members mounted in spaced relation on said supporting elements and coacting therewith to form a cylindrical-shaped frame, each of said annular members comprising a pair of arcuate-shaped sections hinged together so as to be foldable one upon the other when said frame is dismantled, one of said annular members being axially adjustable toward and away from the other said member longitudinally of said supporting elements, and fastening means on said members for securing a curtain or the like in stretched position on said frame.

2. In a device of the class described, the combination of a plurality of supporting elements, a pair of annular members mounted in spaced relation on said supporting elements and coacting therewith to form a cylindrical-shaped frame, each of said annular members comprising a pair of arcuate-shaped sections hinged together so as to be foldable one upon the other when said frame is dismantled, a brace interposed between the ends of each of said sections for strengthening the same and maintaining the shape thereof, one of said annular members being axially adjustable toward and away from the other said member longitudinally of said supporting elements, and fastening means on said members for securing a curtain or the like in stretched position on said frame.

3. In a device of the class described, the combination of a plurality of supporting elements, each comprising a pair of parts hinged together so as to be folded upon each other when said device is to be dismantled and to be longitudinally extended when said device is to be used, one part of each of said elements having a longitudinally disposed slot formed therein, a pair of annular members each comprising a pair of arcuate-shaped parts hingedly connected together so as to be folded one upon the other when said device is dismantled and to be extended so as to be disposed in the same plane when said device is set up for use, one of said annular member being rigidly secured to the ends of the other parts of said supporting elements, said other annular member being adjustably supported to said first-mentioned

parts by clamping means carried thereby and extending through said slots, said supporting elements and annular members when assembled forming a cylindrical-shaped frame adapted to stand on the ends of said supporting element in a vertically disposed position, and fastening means on said annular members for securing a curtain or the like in stretched position on said frame.

4. In a device of the class described, the combination of a plurality of supporting elements, each comprising a pair of parts hinged together so as to be folded upon each other when said device is to be dismantled and to be longitudinally extended when said device is to be used, one part of each of said elements having a longitudinally disposed slot formed therein, a brace on each of said supporting elements adapted to be extended across the hinge joint of said parts for locking said parts in longitudinal alinement, a pair of annular members each comprising a

pair of arcuate-shaped parts hingedly connected together so as to be folded one upon the other when said device is dismantled and to be extended so as to be disposed in the same plane when said device is set up for use, one of said annular members being rigidly secured to the ends of the other parts of said supporting elements, said other annular member being adjustably supported to said first-mentioned parts by clamping means carried thereby and extending through said slots, said supporting elements and annular members when assembled forming a cylindrical-shaped frame adapted to stand on the ends of said supporting elements in a vertically disposed position, and fastening means on said annular members for securing a curtain or the like in stretched position on said frame.

Signed at Chicago this 10 day of Nov. 1919.

STANLEY PASTERNAK.
JOSEPH PASTERNAK.
